METHOD OF SIGNALING

Henri Chireix, Paris, France, assignor to Compagnie Générale de Télégraphie, Paris, France, a corporation of France

Application March 5, 1931, Serial No. 520,309, and in France March 5, 1930

7 Claims. (Cl. 178—44)

It is well known that speech or music can be represented by a series of frequencies which in concentrated form may be symbolically represented by the expression

$$\sum_{n=0}^{\infty} a_n \cos(\Omega_n t - \phi_n) \quad (1)$$

10 a_n designating the amplitude of the component of pulsation Ω_n and of phase displacement ϕ_n .

The normal telephonic modulation caused by any transmitter or emitter of pulsation ω and of amplitude A may be expressed by:

$$15 A \cos \omega t \{ 1 + \sum_{n=0}^{\infty} K_n \cos(\Omega_n t - \phi_n) \} \quad (2)$$

20 K_n being in that case the degree of depth of modulation expressed in percent of the pulsation Ω_n .

It is likewise known that this expression is identical with:

$$25 A \cos \omega t + \sum_{n=0}^{\infty} (AK_n/2) \cos \{(\omega + \Omega_n)t - \phi_n\} + \\ 30 \sum_{n=0}^{\infty} (AK_n/2) \cos \{(\omega - \Omega_n)t + \phi_n\} \quad (3)$$

The first term represents what is called the carrier wave, the second term the upper spectrum or band, the third term the lower spectrum or band.

35 It is interesting, and this has already been done for the commercial telephony (not requiring the same quality of reproduction than music or songs) to eliminate from the transmission either the carrier wave and one of the lateral bands, or simply a lateral band.

This has been done up to the present time exclusively by means of band filters.

40 Considering that, for the components of low frequency of speech, the two bands are very close to each other, it may be realized that it is impossible with "filters" to effect the separation for these low frequencies.

The present invention, which is known as the Chireix system, discloses one method of overcoming the aforementioned difficulty.

45 On the basis of the identity:

$$50 \cos \omega t \cos \Omega t \pm \sin \omega t \sin \Omega t = \cos(\omega \mp \Omega)t \quad (4a)$$

The invention deduces a method which consists in arranging two high frequency pulsating currents in quadrature and to modulate the same respectively by the current spectra, extending

down to the lowest frequencies and having the form:

$$\sum_{n=0}^{\infty} a_n \cos(\Omega_n t - \phi_n) \text{ and } \sum_{n=0}^{\infty} a_n \sin(\Omega_n t - \phi_n) \quad (4b) \quad 65$$

For the application of the method according to the invention a first great difficulty to be solved consists, there being given a spectrum of currents

$$\sum_{n=0}^{\infty} a_n \cos(\Omega_n t - \phi_n) \quad (5)$$

70 to produce, starting out from this spectrum, another spectrum

$$\sum_{n=0}^{\infty} a_n \sin(\Omega_n t - \phi_n) \quad (6) \quad 75 \quad 80$$

identical with the first with respect to the respective amplitudes a_n but representing currents shifted in phase by 90° , this to hold true even for the very low frequencies. This problem can only be solved approximately, but in accordance with the modes of realization furnished by the invention, the solution obtained may be as close as desired.

85 In the accompanying drawings, Figures 1 and 2 illustrate two circuit schemes in accordance with the present invention of obtaining a current in quadrature with the applied current, but having the same amplitude.

90 Figures 3 to 5 illustrate detailed methods of obtaining two currents in quadrature with respect to each other from a source of applied current over a wide range of frequencies.

95 Figures 6 and 7 illustrate two embodiments for use in arrangements such as those illustrated in Figures 1 to 5 for suppressing the carrier and one of its associated side bands without the use of filter circuits.

100 Figures 8 illustrates, in schematic form, the essential elements of a complete system embodying the principles of the present invention wherein reference characters in the boxes represent the numbers of the figures which are shown in detail in the other circuit arrangements.

105 One means of realization is furnished by the circuit of Figure 1 comprising, connected in series with an inductance L , a condenser C , a resistance r and a second resistance r' . The input potential E is supplied by the conductors 1 and 1' between L and C on the one hand and between r and r' on the other hand; the output potential e is collected between the conductors 2 and 2' connected respectively between L and r on the one hand and between C and r' on the other hand; in this circuit, for all the frequencies here

considered, the resistances r and r' are small compared with the inductive and capacitative impedances. If the circuit resonates at the pulsation ω_0 and if $r=r'$ the potential collected between 5 2 and 2' is:

$$e = \frac{Er}{L\omega_0} \{(\omega_0/\omega + \omega/\omega_0)\} \quad (7)$$

This potential varies little when ω/ω_0 varies to 10 both sides of unity and is on the other hand in exact quadrature with E within an infinitely small value close to the second order if the variation of e is considered as infinitely small of the first order.

15 Another means of realization, furnished by the circuit of Figure 2 wherein the impedances shall be small compared to the resistances R represents a variant producing the same results.

20 Nevertheless, the diagrams of Figures 1 and 2 give a much too rough solution of the practical realization of the method.

25 A better solution is furnished by the diagram according to Figure 3 in which Q_1 , P_1 , Q_2 are phase-shifting devices of the type of those of Figures 1 and 2, T a transformer with two secondaries 1, 1' the input leads, 2, 2' an output line for the potential in quadrature, 3, 3' an output line for the potential in phase.

30 The telephonic currents being supplied by 1, 1', there is obtained in ab a potential in quadrature with E , of an amplitude

$$E\alpha\{(\omega/\omega_0 + \omega_0/\omega)\}, \quad (8)$$

α being a certain coefficient due to the device Q_1 .

35 On the other hand there is directly taken at cd , with the aid of a potentiometer, a portion in phase of the potential E . To this co-phasal tension is then added another tension furnished by the transformer T . This potential is produced by the potential ab having traversed a device P_1 identical or similar to Q_1 . It is of the form

$$E\beta\{(\omega/\omega_0 + \omega_0/\omega)^2\}, \quad (9)$$

40 and in phase with E , since it has been subjected to a double phase shift of 90° . The transformer T furnishes likewise a potential which is impressed on a device Q_2 similar to P_1 and Q_1 and which reproduces at ef a potential of the form:

$$E\gamma\{(\omega/\omega_0 + \omega_0/\omega)^3\} \quad (10)$$

45 and which is in quadrature with E since it has been subjected to three successive phase shifts.

50 There will then finally be obtained at 2, 2' a potential in quadrature of the form:

$$E\{\alpha(\omega/\omega_0 + \omega_0/\omega) + \gamma(\omega/\omega_0 + \omega_0/\omega)^3\} \quad (11)$$

55 and at 3, 3' a potential in phase of the form:

$$E\{1 + \beta(\omega/\omega_0 + \omega_0/\omega)^2\} \quad (12)$$

60 By a suitable choice of the parameters α , β and γ these two potentials may be rendered quite equal to each other over a large range of frequencies. Thus, for instance if $\alpha=0.82$, $\beta=0.19$, $\gamma=0.0125$ the difference of the potentials compared to their sum is lower than 2.5% for a range of frequencies from $\omega/10$ to $10\omega_0$, in other words for a spectrum of frequencies going from 1 to 100.

65 It stands to reason, besides, that the method of obtaining the correcting terms by the introduction in the connections of successive correcting devices is a general one and that there may be re-introduced in the lines 2, 2' and 3, 3' respectively, a third corrective term of potential, then a fourth, etc.

70 It will be noted, nevertheless, that, if the relative amplitudes as well as the phase relations are

preserved, the amplitude in absolute value increases if moving away from the geometric average. This fault could be remedied by placing at the input a corrective circuit which in its most simple form may be a simple resonant circuit 80 suitably damped such as represented at C.

85 From the practical point of view the circuit arrangement must be done in the manner as to prevent any shunting at the outgoing end of the phase displacing circuits, and for instance by means of relay tubes, as indicated in Figure 4, which may be understood without further description, the letters and numbers of reference designating the same elements or terminals.

90 A variant of Figure 4 is given in Figure 5. This variant has the purpose to prevent phase displacements which may be introduced by the transformers if these latter are not constructed correctly.

95 Having produced the two systems of currents:

$$\sum_0^n a_n \cos(\Omega_n t - \phi_n)$$

and

$$\sum_0^n a_n \sin(\Omega_n t - \phi_n) \quad (13)$$

100 a means for applying the method of modulation in accordance with the invention is furnished by the connection diagram of Figure 6, given by way of example.

105 Two high frequency potentials in quadrature are branched off the line 1, 1' by means of two tuned circuits I and II, the circuit II obtaining its induction from circuit I. These potentials are impressed on two symmetrical circuits III, IV respectively, of a type known, each comprising tubes or groups of tubes, connected in opposition. The grids of the symmetrical circuit III are fed by means of conductors 7, 7' which are on the other end connected to the two armatures of condenser 11 of the tuned circuit I, provided with two self-inductances, one, 9, being the coupling 110 means with the self-inductance 10 of the tuned circuit II. At the armatures of the condenser 12 of this second tuned circuit are branched the two conductors 8, 8' which feed the grids of the symmetric circuit IV. The grid-cathode circuits 115 of the symmetrical circuits close across center taps on the self-inductances 9, 10, the said taps being connected to the body 15 across polarizing batteries 14, 14', and the cathodes of the tubes are likewise connected to the body 15. The potentials impressed on the circuits III and IV are modulated, for instance according to the system called anode control system or system with constant current, by the outputs coming from the lines 2, 2' and 3, 3' of Figures 4 or 5.

120 If the symmetrical circuits are balanced in the manner that the wave of pulsation ω does not pass, there is collected in the output circuit V by the line 4, 4'

$$\sum_0^n AK_n \cos\{(\omega + \Omega_n)t - \phi_n\} \quad (14)$$

or

$$\sum_0^n AK_n \cos\{(\omega + \Omega_n)t + \phi_n\} \quad (145)$$

130 according to the sign of the connections.

135 If one of the symmetrical circuits is unbalanced,

partly or completely, by eliminating one of its tubes, there is furthermore collected a carrier wave $A \cos \omega t$ or $A \sin \omega t$ according to whether the debalancing affects III or then IV.

5 In one case or the other a system of transmission will exist answering the condition indicated at the beginning of this application.

A particularly interesting application of the method and devices according to the invention 10 resides in broadcasting. The suppression of one of the lateral bands is the means, all other things being otherwise equal, to place in one and the same frequency band twice as many transmissions. It permits, besides, the reduction in half 15 of the shifting band of the receivers and accordingly, due to a more pronounced syntony, the reduction of the influence of the atmospheric strays. In the case of a radio broadcast transmitter functioning according to the principle 20 called the amplification with modulated high frequency, the circuit of Figure 6 would be simply inserted between two stages of high frequency amplification without further complications. For the same reasons the antenna may be tuned closer 25 since the frequency spectrum is reduced by half. In this case by the way, the fact that the amplitudes have a tendency to increase, in spite of the correcting circuit, for the deep notes and the high notes is rather an advantageous item considering the difficulty of a good transmission of the extremities of the spectrum of the acoustic 30 frequencies.

The present invention is particularly useful in 35 various types of short wave systems, especially in multiplex telegraph and telephone communication systems operating either on a code basis or any other suitable basis.

The following example relates to a telephone 40 communication system and is merely mentioned as an illustration, not as a limitation.

The frequencies of the first telephonic transmission P may be written symbolically for a given instant as ΣP ; likewise the frequencies of the second ΣQ . Well understood, the spectra are the same, they are the ones of the voice. By applying the connections of Figures 3, 4 or 5 and 6, the spectrum ΣP may be transposed to the spectrum $\Sigma(F+P)$ or then again to the spectrum $\Sigma(F-P)$, F being a frequency of the order of several thousands per second, so as to separate the new spectrum $\Sigma(F+P)$ or $\Sigma(F-P)$ from the spectrum ΣQ . Then there may be modulated, always according to the circuits of Figures 3, 4 or 5 and 6, the short-wave transmitter by a spectrum 55 of frequencies or a band of frequencies $\Delta\phi$, the spectrum $\Delta\phi$ comprising:

1. The spectrum ΣQ
2. The spectrum $\Sigma(F+P)$ or $\Sigma(F-P)$
3. A frequency F_1

39 At the output of the balanced circuit of Figure 6 we will have $f_0 + \Delta f$, f_0 being the high frequency; assuming:

$$\begin{aligned} & f_0 + \Sigma Q \text{ lateral band} \\ & f_0 + \Sigma(F+P) \text{ lateral band} \\ & f_0 + F_1 \text{ carrier wave} \end{aligned} \quad (15)$$

33 At the reception, the frequency $(f_0 + F_1)$ will act like a carrier wave and after detection we will find the currents:

$$\begin{aligned} & \Sigma(F_1 - Q) \\ & \Sigma(F_1 - F) - P = \Sigma\{(F - F_1) + P\} \end{aligned} \quad (16)$$

which is transposed speech, or transposed and inverted.

35 If for instance $F_1 = 4000 \sim$ per second
 $F = 9000 \sim$ per second

after detection the spectrum of the communication Q will be $\Sigma(4000 - Q)$ and the spectrum of the first communication $\Sigma(5000 + P)$.

These communications may be separated by filters and rendered intelligible after demodulation by heterodynes of 4000 and 5000 periods per second.

They are, furthermore, both unintelligible for any observer not being in possession of the material necessary for the reconstruction.

If it is a case of making $f = 9000$ periods per second, F is made = 4000 periods per second, the communication Q will always be after detection in the spectrum $\Sigma(4000 - Q)$, hence unintelligible, but the transmission P will be directly intelligible, since its spectrum will be

$$\Sigma\{(F - F_1) + P\} = \Sigma P \quad (17)$$

If, inversely, F_1 would be made = 0 and if the modulator is unbalanced so as to let pass f_0 , the communication Q would be directly intelligible (continuous carrier wave) and the communication P would be transposed in the spectrum $\Sigma(F + P)$. Naturally the examples may be varied infinitely and are only given as illustration.

In the case where the transpositions to be effected are only of some thousands of periods, as has been said in regard to the examples for multiplex communications, the diagram of Figure 6 105 may be replaced by a more simple scheme (Figure 7).

Let I, II, III, IV be rotary variable condensers whose capacities may be written:

$$\begin{aligned} C + c \cos \omega t & \text{ for I} \\ C - c \cos \omega t & \text{ for II} \\ C + c \sin \omega t & \text{ for III} \\ C - c \sin \omega t & \text{ for IV} \end{aligned} \quad (18) \quad 110$$

and let V be condensers of equal size and of a capacity Γ large as compared to $C + c$.

Applying on the other hand at 2, 2' and 3, 3' of Figure 7 the spectra furnished by the circuit according to Figure 4 or 5, represented by the expressions:

$$\sum_{n=0}^{\infty} a_n \cos(\Omega_n t - \phi_n) \text{ and } \sum_{n=0}^{\infty} a_n \sin(\Omega_n t - \phi_n) \quad (19) \quad 125$$

the potential at the terminals of condenser V with respect to I can be written:

$$\frac{\int idt}{\Gamma} \quad (20) \quad 130$$

but

$$\frac{\int idt}{C + c \cos \omega t} \sim \sum_{n=0}^{\infty} a_n \cos(\Omega_n t - \phi_n) \quad (21) \quad 135$$

hence

$$\frac{\int idt}{\Gamma} = \sum_{n=0}^{\infty} a_n \cos(\Omega_n t - \phi_n) \times \frac{C + c \cos \omega t}{\Gamma} \quad (22) \quad 140$$

The potential of condenser V with respect to II 145 may likewise be written:

$$\frac{\int idt}{\Gamma} = \sum_{n=0}^{\infty} a_n \cos(\Omega_n t - \phi_n) \times \frac{C - c \cos \omega t}{\Gamma} \quad (23) \quad 150$$

hence the difference of potential between *a* and *b*

$$5 \quad \frac{2c}{\Gamma} \sum_{n=0}^{\infty} a_n (\cos \Omega_n t - \phi_n) \cos \omega t \quad (24)$$

likewise the one between *c* and *d*

$$10 \quad \frac{2c}{\Gamma} \sum_{n=0}^{\infty} a_n (\sin \Omega_n t - \phi_n) \sin \omega t \quad (25)$$

And therefore there is collected between 4, 4' according to the sign adopted a potential of the 15 form:

$$15 \quad \frac{c}{\Gamma} \sum_{n=0}^{\infty} a_n \cos \{(\omega + \Omega_n)t - \phi_n\} \quad (26)$$

20 or

$$25 \quad \frac{c}{\Gamma} \sum_{n=0}^{\infty} a_n \cos \{(\omega - \Omega_n)t + \phi_n\} \quad (26)$$

Accordingly, there may be effected telephonic transpositions by utilizing the circuits of Figure 4 or 5 with a circuit such as that of Figure 7 and, secondly, the suppression of the high 30 frequency carrier wave and one of side bands by applying the spectrum previously obtained to a circuit comprising the arrangements outlined in either Figure 4 or 5 working into the circuit of Figure 6. Such an arrangement is illustrated 35 in Figure 8.

It should be distinctly understood that the invention is not limited to the precise arrangement of parts disclosed herein since various other 40 modifications and organizations may be resorted to without departing from the spirit and scope of the appended claims. For example, the invention may be readily utilized for radio broadcasting, for short wave communication systems and for multiplex telegraph and telephone 45 communication systems.

Having thus described my invention and the operation thereof, what I claim is:

1. A circuit arrangement for obtaining a wave 50 presenting a phase angle of 90 degrees with reference to an applied wave spectrum while preserving substantial equality of amplitude relation throughout the frequency range between currents of each frequency in the obtained wave and the applied spectrum, including a bridge 55 arrangement comprising four elements of which two adjacent elements are respectively an inductance and a capacity, and two others two equal resistances, the value of each of said resistances being greatly different from each of the 60 said pair of impedances, means for applying the wave spectrum to two opposite apices of the bridge, and means for collecting the phase-displaced wave at the other two apices of said bridge.

55 2. Circuit arrangement adapted to obtain from a given wave spectrum two wave spectrums, one presenting the same phase angle as the original wave spectrum, and the other waves spectrum presenting a phase angle of 90 degrees, these 65 two wave spectrums being of like amplitudes, comprising a plurality of circuits associated with the source of current, one of said circuits containing in cascade an even number of phase-displacing circuits causing the change in phase 70 of 90 degrees, and means for superposing the

output currents of these latter phase displacing circuits in a common or joint circuit, another of said plurality of circuits associated with the source of current containing in cascade an odd number of the said phase-shifting circuits, and means adapted to superpose the output currents of these latter circuits in another common or joint circuit. 80

3. In combination, a radio frequency source, a radio communication circuit arrangement 85 adapted to derive from said source two waves presenting a relative phase displacement of 90 degrees, two symmetric circuits passed respectively by each of said waves, means of modulation of the output currents of these circuits respectively by currents of like amplitude, but of a phase displaced 90 degrees, a circuit arrangement as claimed in claim 1 for causing the last mentioned phase displacement, and a common 90 circuit associated with the said symmetric circuits. 95

4. In combination, a Wheatstone bridge arrangement having a variable condenser in each of two adjacent arms thereof, two impedances in the other arms of said bridge, said impedances 100 having values differing greatly from those of said condensers, another Wheatstone bridge similarly constructed to said first bridge, both said bridges being connected together at one of their apices, means for applying at two other opposite 105 apices of each of said bridges two waves of equal amplitude, but in phase quadrature with respect to each other, and terminal connections to the fourth and last apex of each of said bridges for obtaining currents therefrom. 110

5. A combination in accordance with claim 4 characterized in this, that said condensers are of the rotary type. 115

6. In a communication circuit whose characteristics are suitably chosen whereby there is 115 obtained from a wave spectrum two other wave spectrums of equal amplitude, over a large range of frequencies, one of which wave spectrums is in phase and the other of which is 90 degrees out of phase with respect to said first wave spectrum, 120 the method of communication which includes shifting the phase of a portion of the current of the first wave spectrum twice successively, each time 90 degrees with respect to said first wave spectrum in order to obtain one of said desired 125 wave spectrums and shifting the phase of the current a third successive time again by 90 degrees to obtain the other desired wave spectrum. 130

7. In a communication circuit whose characteristics are suitably chosen whereby there is 130 obtained from a wave spectrum two other wave spectrums of equal amplitude over a large range of frequencies, one of which wave spectrums is in phase and the other of which is 90 degrees out of phase with respect to said first wave spectrum, 135 the method of communication which includes shifting the phase of a portion of the current of the first wave spectrum twice successively, each time 90 degrees with respect to said first wave spectrum and adding to said twice shifted wave 140 spectrum another portion of said first wave spectrum obtained without any phase shift in order to obtain one of said desired wave spectrums, and shifting the phase of a portion of the current of the first wave spectrum a third successive time 145 again by 90 degrees and adding thereto still another portion of said first wave spectrum obtained merely by a 90 degrees phase shift in order to obtain the other desired wave spectrum. 150
